UNITED STATES PATENT OFFICE.

HUMPHREY EVANS, OF MILWAUKEE, WISCONSIN, ASSIGNOR TO HOLEPROOF HOSIERY CO., OF MILWAUKEE, WISCONSIN; A CORPORATION OF WISCONSIN.

KNITTING-MACHINE.

1,335,281.

Specification of Letters Patent. Patented Mar. 30, 1920.

Application filed July 19, 1918. Serial No. 245,601.

To all whom it may concern:

Be it known that I, HUMPHREY EVANS, a citizen of the United States, residing at Milwaukee, in the county of Milwaukee and State of Wisconsin, have invented certain new and useful Improvements in Knitting-Machines, of which the following is a specification, reference being had to the accompanying drawing, forming a part thereof.

10 This invention relates more particularly to circular knitting machines of the socalled Hemphill "Banner" type, as shown and described in United States Letters Patent No. 933,443, dated September 7, 1909, which are 15 adapted to knit legs and feet on ribbed tops knitted on other machines known as "ribbers".

The main objects of the invention are to facilitate the operation known as "topping" by which ribbed stocking tops knitted on ribbers are transferred into other machines for knitting the rest of the stockings; to avoid the hand operations and adjustments which with machines of the type referred 25 to as heretofore made, require experience, skill and care on the part of operators; to save time; to prevent injury to the machines and the work; and generally to improve the construction and operation of machines used for this class of work.

It consists in the construction, arrangement and combination of parts as herein-after particularly described and pointed out in the claims.

35 In the accompanying drawing like characters designate the same parts in the several figures.

Figure 1 is a front elevation of a portion of a machine of the type referred to embodying the invention; Fig. 2 is a side elevation of the machine as viewed from the right relative to Fig. 1; Fig. 3 is a side elevation as viewed from the left relative to Fig. 1, of the pawl and ratchet mechanism 40 for operating the pattern drum, pattern chain, and belt shifting cam which control the operations of the machine; Figs. 4 and 45 5 are front elevations similar to that of Fig. 1, showing parts of the mechanism in different positions for shifting the stitch cam block and controlling the operation of the 50 yarn carriers; Fig. 6 is a plan view of a portion of the latch ring, yarn carriers and needle cylinder; and Fig. 7 is a vertical section of the latch ring and upper part of the

needle cylinder looking toward the yarn carriers and showing a brush on the latch ring for insuring the entry of the yarn to be knitted to the ribbed tops into the hooks of the needles.

60 The machine comprises a rotary needle cylinder 1, provided as shown in Fig. 2, with long butt needles 2, and short butt needles 3; a latch ring 4, pivotally mounted at 5 on a post 6, supported on the frame 7 behind the needle cylinder; a sinker ring 8, a vertically adjustable cam plate or ring 9, provided with needle lowering, lifting and leveling cams 10; and a cam block 11, shiftable radially on the cam plate or ring 9 toward 70 and from the needle cylinder 1, and provided with the usual stitch cams 12 and 13.

75 Yarn carriers 15, 15', are pivotally mounted on one side of the latch ring 4, and springs 16 fastened to the latch ring, tend to turn the carriers downward into and hold them in operative position.

80 Lifting levers 18, are fulcrumed side by side in a hollow post 19, mounted on a frame 7 at the right hand of the needle cylinder 80 in position to engage with and to raise the yarn carriers 15, 15', out of operative position when the latch ring 4 is turned down, as shown in Fig. 1, into operative position over the needle cylinder.

85 The levers 18 are connected by rods or wires 22 (one of which is shown in Fig. 1) with levers 23, 23'; actuated by cam blocks on the pattern drum 24, for lifting and holding the yarn carriers 15, 15', out of operative 90 position at the proper times.

95 The pattern drum 24 is fixed on a shaft 26, and on this shaft is fixed a ratchet wheel 27, for turning the drum to control various operations of the machine.

Next to the ratchet wheel a chain wheel 29, to which a ratchet wheel 30 is attached, is loosely mounted on the shaft 26.

100 As shown in Fig. 3, the ratchet wheels 27 and 30 are actuated by pawls 33 and 34, pivoted to a rocker arm 35 of a segment gear 36, which has actuating connections with the drive pulleys hereinafter mentioned, and serves to impart a reciprocating movement to the needle cylinder.

105 A pawl lifter 40, pivotally mounted on the machine frame 7, controls the operation of the ratchet wheel 27 and pattern drum 24 by the pawl 33. A spring 41, shown in Fig. 3, tends to turn the pawl lifter 40 110.

into position to lift the pawl 33 and hold it out of engagement with the ratchet wheel 27. A lug 42, projecting from one side of the pawl lifter 40 over the ratchet wheel 27, engages one side of the pattern chain 43, which is mounted on the sprocket wheel 29 and is provided with lugs as usual in this class of machines for controlling the movement of the pattern drum 24 and of the belt shifting cam 44, which is fixed on the shaft 26.

The machine is provided with fast and slow speed drive pulleys 47 and 48, and with a loose pulley 49, which are mounted side by side in axial alignment with a drive shaft 50, through which both continuous rotary and reciprocating movements are imparted to the needle cylinder.

A belt shifter 53, having parallel rods or bars 54 and 55, guided in the frame 7, is provided with an arm 56, projecting into the path of the stepped rim of the cam 44. A spring 58, tends to move the belt shifter 53 toward the frame 7 and to shift the belt 59 from the loose pulley 49 toward the fast speed drive pulley 47.

A spring actuated latch 61, is adapted to automatically engage with a notch in the rod 54 to lock and hold the belt shifter 53 in its stopping position with the belt 59 on the loose pulley 49, as shown in Fig. 1. The latch 61 is adapted to be manually disengaged from the rod 54 for starting the machine.

The machine is provided with a spring actuated hook 63, pivotally mounted on the post 19 and adapted by engagement with a stud 64 on the latch ring to lock and hold the latch ring in place when it is turned down into operative position, as shown in Figs. 1 and 2.

The cam block 11 is withdrawn into inoperative position at the proper time by a cam block or projection 66 on the pattern drum 24 in the path of a lever or follower 67, connected by a rod 68 with a bell crank lever 69, which is connected by a link 70 with the cam block. A spring 72 between the outer end of the cam block 11 and a bracket on the cam plate or ring 9, tends to shift the cam block inwardly toward the needle cylinder.

As thus far described, the machine is like or similar in construction and operation to that shown and described in the Hemphill patent hereinbefore mentioned.

To insure the stopping of the machine with its parts in proper position, to level or restore all the needles to normal position preparatory to knitting the leg and foot of a stocking to a ribbed top, to insure the proper advance of the stitch cam block into operative position, and to enter the yarn or yarns to be knit to the top at the proper time without the manual operations and ad-

justments of the machine heretofore necessary and requiring time, care and skill on the part of the operator, the following additions and changes constituting the present invention, are made in the machine:

A stop 74 is pivotally mounted on the cam block 11, and adapted by engagement with the lifting levers 18 to arrest and hold the yarn carriers 15, 15' out of operative position when the cam block 11 with the stitch cams thereon, is advanced against the short butt needles and said lifting levers are released by the cam blocks or projections on the pattern drum 24. This stop is formed with three arms, a middle upwardly projecting arm of sufficient width at its upper end, as shown in Fig. 2, to coöperate with the several lifting levers, an arm projecting horizontally inward toward the needle cylinder, and an outwardly projecting weighted arm tending to swing and hold the middle upwardly projecting arm outwardly and provided with an adjustable stop screw 75 for limiting the outward movement of the middle arm in position to properly coöperate with the lifting levers 18.

A cam or incline 77, is adjustably mounted on the sinker ring 8, which rotates with the needle cylinder in position to engage with the inwardly projecting arm of the stop 74 and turn its middle arm inwardly toward the needle cylinder to release the lifting levers 18 and the yarn carriers which they support and permit them to descend into operative position at a predetermined point in the revolution of the needle cylinder when the cam block 11 is advanced.

To automatically disengage the hook 63 from the stud 64 and release the latch ring 4 when the cam block 11 is withdrawn from operative position and the machine is stopped, a lever or arm 80, is pivoted on the outer end of the cam block 11, transversely to the hook, with the lower end of which it is adapted to engage as the cam block is withdrawn from the needle cylinder into inoperative position. A spring 81, shown on Fig. 2, tends to turn the front end of the lever or arm 80 upwardly and to hold it in position to engage with the lower end of the hook 63.

To release the hook 63 and permit it to resume its operative position for engagement with the latch ring when it is again turned down into its operative position after the cam block 11 has been withdrawn and the machine has been stopped, an incline 84 is adjustably attached to the post 19 in the path of the lever or arm 80, which it is adapted to force downwardly out of engagement with the lower end of the hook as the cam block is withdrawn to inoperative position. The incline 84 is also adapted to guide the lever or arm 80 below and back of the lower end of the hook 63 when the cam

block 11 is advanced, so that when the cam block is again withdrawn, said lever or arm will be in position to engage with the hook and release the latch ring.

5 To properly stop the machine, level the needles and cause the belt shifting cam to clear the belt shifter preparatory to inserting in the machine a transfer ring with a stocking top looped on its quills, and again starting the machine by simply releasing the belt shifter, the pattern chain 43 is provided with a low lug 86, which by engagement at the proper time with the lug 42, lowers the pawl lifter 40, as shown in Fig. 3, into position to allow the pawl 33 to engage successively one at a time with three teeth, 103, 104, 105, of the ratchet wheel 27. Of these three teeth the intermediate tooth 104 is longer than the other two. The cam 44 is formed, as shown in Fig. 1, in the path of the arm 56 of the belt shifter and in corresponding angular relation to the first two of said three teeth of the ratchet wheel 27 engaged by the pawl 33 as the lug 42 rides over the pattern chain lug 86, with an incline 88, for first shifting the belt from the pulley 47 upon the pulley 48, a slow speed step 89 for holding the belt on the slow speed pulley 48 while the cam block 11 is withdrawn and the needles are leveled, and an incline 90 for finally shifting the belt from the pulley 48 upon the pulley 49, and stopping the machine.

The cam 44 is also formed, as shown in Fig. 2, with a slow speed step 92, immediately following the incline 90, for holding the belt on the slow speed pulley 48 when the machine is first started, until the loops of yarn on the needles are carried below the sinkers, the stitch cams on the cam block 11 are fully advanced into engagement with the long butt needles, and the yarn carrier 15' is lowered into operative position.

45 The pattern chain 43 is also provided with a short low lug 106, closely following the lug 86, for lowering the pawl 33 into position to engage another tooth 107 of the ratchet wheel 27 to turn the cam 44 and carry the step 92 out of engagement with the arm 56, thereby permitting the belt shifter to shift the belt from the slow speed pulley 48 upon the fast speed pulley 47.

A yielding dog 94, pivotally mounted on the cam 44, projects normally into the path of a tooth 95 on the rocker arm shaft 96, as shown in Fig. 2, and is adapted to be engaged by said tooth to turn the cam 44 forward on the backward throw of the rocker arm 35, a distance corresponding with a part of the long tooth 104 of the ratchet wheel 27, while the slow speed step 89 of the cam is in engagement with the arm 56 of the belt shifter.

65 The machine may be equipped by pro-

viding the pattern drum 24 with cam blocks or projections of proper arrangement and extent to lower one or more of the yarn carriers into operative position when the machine is started, for knitting one or more 70 yarns into the ribbed top.

For the purpose of illustration and explanation, the pattern drum is shown in Fig. 1 as provided with a cam block or projection 97, to coöperate with a single lever or follower 23', for releasing the yarn carrier 15' and knitting a single yarn into the top when the machine is started. This cam block or projection terminates at its trailing end in line with the cam block 66, which controls 80 the release and advance of the stitch cam block 11 into operative position so as to simultaneously release said yarn carrier and stitch cam block.

To insure the proper entry of the yarn 85 guided by the carrier 15' into the hooks of the needles when the carrier is lowered into operative position, the latch ring may be provided as shown in Figs. 5, 6 and 7, with a brush 99, the spindle of which is mounted 90 in an eccentric bushing 100, for the proper adjustment of the brush toward and from the needle cylinder.

In the operation of the machine, which is shown in Figs. 1 and 2, in condition to 95 be started, a ribbed top having been properly inserted in the machine by means of a transfer ring of the usual construction, with a course of loops adjacent to the unfinished end of the top drawn down over the hooks 100 of the needles, which have been previously leveled, while the cam plate or ring 9 is in its lowest position, the transfer ring having been removed and the latch ring turned down and locked in operative position as 105 shown, the machine is started by the operator lifting the latch 61 out of engagement with the notch in the bar 54. The belt shifter 53 is thereupon shifted to the left, as shown in Fig. 1, carrying the belt 59 110 from the loose pulley 49 upon the slow speed pulley 48, and the arm 56 into engagement with the slow speed step 92. With the first forward throw of the rocker arm 35, the pattern drum 24 is advanced by the engagement of the pawl 33 with the tooth 105 of the ratchet wheel 27, and the cam blocks 66 and 97 are carried out of engagement 115 with the levers or followers 67 and 23', thereby simultaneously releasing the cam 120 block 11 and the lifting lever 18 which supports the yarn carrier 15'. The cam block 11 with the stitch cams, is thereupon advanced by the spring 72 against the short butt needles, and said lever 18 is caught on 125 the stop 74, thereby arresting the downward movement of the yarn carrier 15' which is thus temporarily held out of operative position, as shown in Fig. 4, until the inwardly projecting arm of the stop is engaged by the 130

cam 77 and the stop is thereby disengaged from the lever 18 and said yarn carrier is permitted to descend into operative position, as shown in Fig. 5. This occurs at a predetermined point in the rotation of the needle cylinder, say from five to ten needles in advance of the long butt needles with which the knitting begins. As the long butt needles pass the stitch cams, they are thrust upwardly and drawn downward to catch the yarn and knit it into the top in the usual manner. As soon as the short butt needles clear the cam block 11, it is further and completely advanced by the spring 72 into position to engage with and actuate the short butt needles as they are brought by the rotation of the needle cylinder into operative position.

The rotation of the needle cylinder at slow speed while the arm 56 of the belt shifter engages the slow speed step 92 of the cam 44, insures the complete advance of the cam block 11 by the spring 72 into position to properly engage with the short butt needles, and prevents the centrifugal action of the long butt needles running at fast speed in frictional engagement with the stitch cams, for arresting the advance of the cam block by said spring before it reaches its final position for the operation of both long and short butt needles. As soon as the stitch cam block 11 has thus been completely advanced into operative position, the short lug 106 on the pattern chain engaging the lug 42, lowers the pawl lifter 40 into position long enough to engage the next tooth 107 of the ratchet wheel and turn the slow speed step 92 of the cam 44 out of engagement with the arm 56. The belt shifter 53 being thus released, is thereupon moved by its spring 58 farther to the left and carries the belt 59 from the slow speed pulley 48 upon the fast speed pulley 47.

The machine then continues to operate automatically in the usual way until a stocking is completed. After a number of plain raveling courses have been knitted on the toe, the cam block or projection 97 is brought with the rotation of the pattern drum 24 into engagement with the lever or follower 23' and through the connections hereinbefore described, lifts the yarn carrier 15' into inoperative position, as shown in Fig. 1. The raveling or final courses of the stocking may be knitted with one or more yarns guided and controlled by any one or more of the yarn carriers. The cam block 66 is then brought into engagement with the lever or follower 67 and through the connections hereinbefore described, withdraw the cam block 11 and the stitch cams from the needle cylinder. As the cam block is shifted away from the needle cylinder, the lever or arm 80 engaging the lower end of the hook 63, disengages the

hook from the stud 64 and releases the latch ring 4, which is thereupon turned upward and backward out of operative position by a spring 102 with which machines of this kind are usually provided, as shown in Fig. 2. 70

After the latch ring 4 has been released by the hook 63 and has been turned up and back by its spring 102, as above stated, the lever or arm 80 is forced down by the incline 84 out of engagement with the lower end of the hook, which is thus released and returned to its normal operative position by its spring, in readiness to engage with the stud 64 and thereby lock the latch ring 4 in place, when it is again turned down by the operator into operative position for knitting another stocking.

When the yarn carrier 15' is raised to inoperative position as shown in Fig. 1, by its lifting lever 18, the stop 74 is released and is restored by its weighted arm to its normal position for engagement with the lifting lever when it is again released preliminary to the yarn carrier being turned down by its spring 16 into operative position. 85

After the stop 74 has been disengaged by the cam 77 from the lifting lever 18 and said lever has descended to the position shown in Fig. 5, it holds the inwardly projecting arm 95 of the stop below the path of said cam until the lifting lever with the yarn carrier which it supports, is again raised.

After the yarn carrier 15' has been lifted, and the cam block 11 withdrawn from operative position as explained, the incline 88 of the cam 44 having been brought again by the intermittent rotation of the cam to the arm 56, the lug 86 on the pattern chain engaging with the lug 42, lowers the pawl lifter 40 to the position shown in Fig. 3, and upon the next forward throw of the rocker arm 35, the pawl 33 engaging the tooth 103 of the ratchet wheel 27, turns the cam forward a distance corresponding with 100 said incline, and shifts the belt from the fast speed pulley 47 upon the slow speed pulley 48. With the next backward throw of the rocker arm 35, the tooth 95 engaging the dog 94, turns the cam 44 while the slow speed step 89 engages the arm 56, an interval corresponding with a portion of the long tooth 104 of the ratchet wheel 27, during which the cam block 11 is withdrawn while the short butt needles are passing it, and then the needle cylinder making one or more complete revolutions, the cams 10 bring all the needles to the same level with their hooks projecting a short distance above the needle cylinder in position to receive loops of 115 another top from the quills of a transfer ring. With the next forward throw of the rocker arm 35 the pawl 33 picks up the long tooth 104 of said ratchet wheel and carries the incline 90 of the cam 44 past the arm 56, 120 125 130

thereby shifting the belt from the slow speed pulley 48 upon the loose pulley 49, and stopping the machine with the various movable parts thereof in position, as shown in Figs. 5, 1, 2 and 3, for immediately starting to knit a stocking and foot upon another top.

The tooth 104 of the ratchet wheel 33 is made long so that the incline 90 of the cam 44 will be carried past and clear the arm 56, 10 as shown in Fig. 2, by the final forward thrust of the pawl 33, and will permit the belt shifter 53 to be thrown back to the left by the spring 58 when the latch is lifted by the operator for starting the machine, as 15 above explained.

When the belt shifter 53 reaches the limit of its movement to the right, the latch 61 drops into the notch in the rod 54 and locks it in that position, the high projection of the 20 cam 44 at the end of the incline 90 having cleared the arm 56, as shown in Fig. 2, thereby leaving the belt shifter free to be moved by its spring 58 to the left, when it is again released by the operator for starting 25 the machine. The dog 94 yields inwardly to pass the arm 56 and tooth 95.

When the machine is again started, the pawl 33 on its first forward thrust engages with the tooth 105 and carries the cam 30 blocks 66 and 97 out of engagement with the levers 67 and 23', thereby releasing the cam block 11 and the yarn carrier 15', as hereinbefore explained.

Various changes in details of construction 35 and arrangement of parts of the machine may be made without departure from the principle and scope of the invention as defined in the following claims.

I claim:

40. 1. In a knitting machine the combination with the needle cylinder, latch ring and shiftable cam block, of a pivoted hook adapted to engage and hold the latch ring in operative position, an arm pivoted on the cam block and adapted to disengage the hook from the latch ring when the cam block is shifted away from the needle cylinder, and an incline in the path of said arm adapted to disengage it from and release the hook 50 after the hook has released the latch ring.

2. In a knitting machine the combination with a needle cylinder provided with needles having long and short butts, a latch ring pivotally mounted on the machine frame, a 55 yarn carrier pivotally mounted on the latch ring, a lever fulcrumed on the machine frame in position to coöperate with the yarn carrier when the latch ring is in operative position, mechanism for operating said lever to lift the yarn carrier out of operative position, a cam block shiftable toward and from the needle cylinder, mechanism for shifting the cam block away from the needle cylinder at the proper time, and a 60 spring tending to shift the cam block to-

ward the cylinder, of a stop pivotally mounted on the cam block and adapted by engagement with said lever to hold the yarn carrier out of operative position when the cam block is advanced by its spring to an 70 intermediate position against the short needle butts, and a cam mounted on the needle cylinder and adapted to shift said stop, release the lifting lever and yarn carrier and allow the yarn carrier to drop into 75 operative position at a predetermined point in the rotation of the needle cylinder a short distance in advance of the long butt needles being brought into action by the advance of said cam block. 80

3. In a knitting machine the combination with the needle cylinder, shiftable cam block, a spring tending to shift the cam block toward the cylinder into operative position, a latch ring pivoted to the machine 85 frame, mechanism comprising a cam on the pattern drum for withdrawing the cam block into inoperative position, a yarn carrier pivoted on the latch ring, a lever for lifting the yarn carrier out of operative position, and mechanism comprising another cam on the pattern drum for releasing said lifting lever when the cam block is released and shifted toward operative position, of a stop pivoted on the cam block and adapted 90 when the cam block is advanced toward the needle cylinder into an intermediate position to engage said lifting lever and hold the yarn carrier out of operative position, and a cam mounted on the needle cylinder 95 and adapted to shift the stop, release the lifting lever and permit the yarn carrier to assume its operative position at a predetermined point in the rotation of the needle cylinder. 100

4. In a knitting machine the combination with the needle cylinder provided with long and short butt needles, the latch ring, a yarn carrier pivoted on the latch ring, a yarn carrier lifting lever, mechanism for operating said lever to lift the yarn carrier out of operative position, a cam block shiftable toward and from the needle cylinder, mechanism for withdrawing the cam block into inoperative position, and a spring tending 110 to shift the cam block toward the cylinder, of a stop pivoted on the cam block and adapted when the cam block is partially advanced against the short needle butts and the lifting lever is released by its operating 115 mechanism to engage with said lever and hold the yarn carrier out of operative position, and a cam rotating with the needle cylinder and adapted to shift said stop and release the lifting lever and yarn carrier, the stop being adapted to be held by engagement with the lifting lever out of the path of said cam when the cam block is fully advanced. 120

5. In a knitting machine the combination 125

tion with the needle cylinder, latch ring, a cam block shiftable toward and from the needle cylinder, a spring tending to shift the cam block toward said cylinder, and 5 mechanism for withdrawing the cam block into inoperative position, of a hook for holding the latch ring in operative position, an arm pivoted on the cam block transversely to the hook and adapted to disengage the 10 hook from the latch ring when the cam block is withdrawn from the needle cylinder.

6. In a knitting machine the combination 15 with the needle cylinder, a stitch cam block movable toward and from the needle cylinder into and out of operative position, fast speed, slow speed and loose pulleys, and a belt shifter tending to shift the belt toward the fast speed pulley, of a belt shifting cam 20 provided with steps and inclines adapted by engagement with the belt shifter to first shift the belt from the fast speed to the slow speed pulley, then to hold the shifter in slow speed position for a number of turns 25 of the needle cylinder and finally to shift the belt from the slow speed to the loose pulley and stop the machine; a ratchet wheel fixed on the cam shaft, a chain wheel provided with a ratchet wheel loosely mounted 30 on the cam shaft, a rocker arm having an actuating connection and provided with pawls for turning said ratchet wheels, a pawl lifter controlling engagement of one 35 mounted on the chain wheel and provided with a lug for lowering the pawl lifter into position to engage with successive teeth of the first ratchet wheel one at a time on each forward throw of the rocker arm, and a

tooth on the rocker arm shaft adapted by 40 engagement with a dog on the belt shifting cam to turn said cam on the backward throw of the rocker arm an interval between successive movements thereof by the first ratchet wheel and its pawl.

7. In a knitting machine the combination 45 with a rotary needle cylinder provided with needles having long and short butts, a latch ring pivotally mounted on the machine frame, a yarn carrier pivotally mounted on 50 the latch ring, a lever fulcrumed on the machine frame in position to coöperate with the yarn carrier when the latch ring is in normal operative position, mechanism for operating said lever to shift the yarn carrier out of operative position at the proper time, a cam block shiftable toward and from the needle cylinder and provided with knitting cams, mechanism for withdrawing the cam block into inoperative position at the 55 proper time, and means tending to advance the cam block into operative position, of a stop movably mounted on the cam block and adapted by engagement with said lever to hold the yarn carrier out of operative position after the lifting lever and the cam block are released and the cam block is advanced to an intermediate position against the short needle butts, and a cam on the needle cylinder adapted to shift said stop, release the lifting lever and allow the yarn carrier to assume its operative position at a predetermined point in the rotation of the 60 needle cylinder.

In testimony whereof I hereto affix my 65 signature.

HUMPHREY EVANS.
